SINGLE-ANODE MERCURY-ARC RECTIFIER

Bjarne Storsand, Zurich, Switzerland, assignor to
 Maschinenfabrik Oerlikon, Zurich-Oerlikon,
 Switzerland, a Swiss firm

Application July 28, 1945, Serial No. 607,528

In Switzerland June 8, 1944

2 Claims. (Cl. 250—27.5)

1

The present invention relates to a new and improved single-anode mercury-arc rectifier and more particularly to rectifiers of the said type with permanent excitation.

It is known that the condensed mercury which flows from the tank of a single anode mercury-arc rectifier with permanent excitation may, in some cases, connect during a brief instant the tank with the cathode, causing thus the extinction of the auxiliary arc. The duration of this connection may be of a hundredth of a second or less. This will appear especially after a rectifier has been a long time in operation, the mercury being then somehow soiled.

The main object of the invention is to provide means to prevent these disturbances. According to the invention the said object is attained by putting a baffle device on the return way of the mercury, the stream of the back-flowing mercury being divided into such little parts, that a shunting of the cathode insulation becomes impossible, even if the mercury should be very soiled.

It would be of advantage if the baffle would serve at the same time as a filter. Normal filterings have proved to be useful by multianode rectifiers, but they are not satisfactory for this purpose. On the other hand, a filter-ring with many little catch chambers may be very useful. These catch chambers permit only a tiny quantity of mercury to flow-off from each of them, thus preventing the formation of a long flash of mercury, which would connect the tank with the cathode.

In the accompanying drawing a preferred construction of the new device is shown by way of an example.

Fig. 1 shows part of a rectifier in sectional elevation.

Fig. 2 is a horizontal section.

The new baffle device comprises within a tank 6 of a rectifier, a ring 1 running concentrically to the wall of the tank 6 at some small distance apart. Between the wall of tank 6 and the ring 1 division walls are provided dividing the annular space into a number of cells 2. For each cell a channel 3 is provided in said ring 1 running tangentially to said ring. 4 denotes the cathode and 5 an insulating ring arranged be-

tween the cathode 5 and the wall of the tank 6.

It is preferable that the baffle device should not be fitted at the proximity of the cathode aperture, but near the wall of the tank 6, well above the cathode 4, in order that the speed of the mercury shall be as high as possible while it flows into the cathode 4. The channels 3 provided in the cells 2 for the outlet of the mercury shall be preferably so inclined that the mercury will flow nearly tangentially to the cathode 4.

What I wish to secure by United States Letters Patent is:

1. In a single anode mercury arc rectifier, a tank having an upright circular wall and a downwardly tapering bottom wall with a circular aperture therein closed by a cathode member, a ring-shaped baffle within said tank and uniformly spaced from the circular wall thereof and resting on said bottom wall, said ring-shaped baffle being provided with radially outwardly extending walls engaging the circular wall of said tank, thereby dividing the annular space between said wall and said ring-shaped baffle into a series of individual cells, and channels extending through said ring-shaped baffle adapted to discharge any mercury collected in said cells and direct it toward the circular aperture in said bottom wall.

2. In a single anode mercury arc rectifier, a tank having an upright circular wall and a downwardly tapering bottom wall with a circular aperture therein closed by a cathode member, a ring-shaped baffle within said tank and uniformly spaced from the circular wall thereof and resting on said bottom wall, said ring-shaped baffle being provided with radially outwardly extending walls engaging the circular wall of said tank, thereby dividing the annular space between said wall and said ring-shaped baffle into a series of individual cells, and channels extending through said ring-shaped baffle and disposed substantially tangentially with respect to the circular aperture in said bottom wall, said channels being adapted to discharge any mercury collected in said cells and direct it toward the circular aperture in said bottom wall.

BJARNE STORSAND.
